UNITED STATES PATENT OFFICE.

JOSEPH WILLIAM BATES, OF MINNEAPOLIS, MINNESOTA.

COIN-CONTROLLED MECHANISM FOR TURNSTILES.

1,271,651.

Specification of Letters Patent.

Patented July 9, 1918.

Application filed August 31, 1914. Serial No. 859,272.

To all whom it may concern:

Be it known that I, JOSEPH WILLIAM BATES, a citizen of the United States, resident of Minneapolis, in the county of Hennepin and State of Minnesota, have invented certain new and useful Improvements in Coin-Controlled Mechanism for Turnstiles, of which the following is a specification.

This invention relates to improvements in coin controlled mechanism for turnstiles so arranged that before the turnstile can be operated a coin of the proper denomination must be placed in the machine and a lever operated by the attendant, which causes the coin to be deposited in a coin receptacle and releases a device that is engaged by the turnstile, thereby permitting the turnstile to turn one step to permit the passage of a single person. The mechanism is then automatically re-set and locked and cannot be again operated even by the attendant until another coin has been deposited.

The invention consists generally in the constructions and combinations hereinafter described and particularly pointed out in the claims.

In the accompanying drawings forming part of this specification.

Figure 1 is a vertical section, of a device embodying my invention, the lower part being broken away,

Fig. 2 is a section on line 2—2 of Fig. 1, looking in the direction of the arrow,

Fig. 3 is a section on the same line as Fig. 2, but showing the parts in different position,

Fig. 4 is a section on line 4—4 of Fig. 1, looking in the direction of the arrow.

Fig. 5 is a detail view showing the arrangement of the star wheel and the lever that is operated by the attendant to release the star wheel after the deposit of the coin.

Fig. 6 is a plan view showing the arrangement of a turnstile in connection with the coin-controlled mechanism,

Fig. 7 is a plan view of the mechanism partly broken away,

Fig. 8 is a detail showing the arrangement of the adjustable controlling plate, adjusted to receive a fifty-cent coin,

Fig. 9 is a similar view of the same device adjusted to receive a twenty-five-cent coin,

Fig. 10 is a detail of the lower part of the base showing the manner in which the two parts are overlapped and united,

55

Fig. 11 is a plan view and Fig. 12 a side elevation of one of the guards on the cover showing means for regulating the length and width of the receiving slot.

60

Fig. 13 is a detail showing a counter.

65

In all of the drawings, 2 represents the casing in which the mechanism is inclosed. This casing is preferably divided into an upper and a lower chamber by a horizontal partition 3. The lower chamber has preferably a door or removable panel 4 through which access may be had to the interior of the chamber. The lower chamber is designed to contain a coin receptacle or money box 5 having at the top one or more coin-receiving openings 6 and coin guides 7. The horizontal partition 3 is provided with an opening 8 above each of the coin guides 7. The upper chamber contains the coin-controlled mechanism proper, and this mechanism is preferably mounted upon a suitable base 9 and is entirely disconnected from the casing 2, so that it may readily be removed therefrom by lifting the same out through the top of the casing.

80

The casing is provided with a removable cover 10, which may be secured thereto by any suitable means. This top plate 10 is provided with coin-receiving slots 11 and guards 12, the openings at the bottom of the guards being of suitable size to correspond to the size of the coin intended to be inserted through such guard. The cover is also preferably provided with a raised central portion 13 in the rear of said guards 12, 85 which forms a recess upon the under side of the cover into which the controlling plate for the locking dog may rise as hereinafter described.

90

The base 9 of the coin-controlled mechanism is preferably formed of two overlapping parts as shown by the detailed view, Fig. 10. Each part of said base is provided with an upright frame consisting preferably of a vertical standard 14, the substantially 95

100

X-shaped standard 15 and the transverse top bar 16. These parts are all preferably formed integrally with the section of the base 9.

- 5 The ends of the bars 16 are preferably connected by a plate 16'. Bearings 17 are preferably formed near the center of the standards 15, and in these bearings is mounted a horizontal shaft 18, which carries near 10 its end, outside of the casing 2, a star-wheel 19. The turnstile is provided with an upright shaft 20 and with a series of horizontal arms 21. The turnstile is arranged to be rotated in the direction of the arrow *a*, 15 Fig. 6. The end of each arm 21, as the turnstile is rotated, comes in contact with one of the arms of the star-wheel 19. Said turnstile can be turned only when the star-wheel is released.
- 20 Mounted upon the shaft 18 is a disk 22 having a series of ratchet teeth 23 upon its circumference. These ratchet teeth correspond in number to the arms of the star-wheel 19. A locking dog 24 is pivoted upon 25 a rod 25 connecting the upper ends of the standards 14. The end of this dog rests by gravity upon the edge of the wheel 22 and is adapted to engage the ratchet teeth 23, and, when in engagement with any one of 30 said teeth, to prevent the shaft 18, the star-wheel 19, and the turn stile, from turning.

A rock shaft 26 extending parallel to the shaft 18 is mounted in suitable lugs 27 upon the base 9. A ratchet wheel 28 is secured 35 upon the shaft 18 preferably near one end thereof. A dog 29 is pivotally supported upon the shaft 26, and arranged in position to engage the ratchet wheel 28, locking said wheel and the shaft 18 at all times against 40 backward movement.

Arranged beneath each of the coin-receiving slots 11, in the cover or top plate of the casing, is a coin-receiving way preferably formed by two parallel plates 30 and 31 arranged with a space between them of sufficient width to receive the coin designed to be deposited in this particular slot. The coin way is provided with a bottom plate 32, which forms a support for the coin 45 when it is dropped into the machine as shown in Fig. 4 of the drawings. A push plate 33 is arranged in the coin way and is adapted to slide forward and back therein. Its normal position is shown in Fig. 4. It 50 is here shown at the rear end of the way, permitting the coin to be dropped into the way in front of said push plate. Upright arms 34 are secured to the shaft 26. These arms extend to the upper end of the frame 55 of the machine and support at their upper ends a transverse rod 35, which passes through the push plate 33. The shaft 26 is also provided with a lever 36 arranged outside the casing 2, as shown in Fig. 1 of 60 the drawings. This lever is in position to

be grasped by the attendant and to be moved for the purpose of rocking the shaft 26. The cross-bars 16 of the machine frame are provided with horizontal slots 37 and the walls of the coin ways are provided 70 with similar slots (see Fig. 3). The rod 35 extends through these slots, which permit said rod to move forward and back reciprocating the push plate 33 in the coin way. Arranged with their upper ends in the same 75 vertical plane with the coin ways are the coin chutes 38. The upper ends of these coin chutes coincide with the forward end of the coin ways; and the lower ends of said chutes come over the openings 8 in the 80 partition 3. The bottom 32 of each of these coin ways terminates at the edge of the corresponding coin chute as shown in Fig. 4 of the drawing. Connected with each side of the dog 24 is a controlling plate 39. These 85 plates project forward into the coin ways and extend above the upper ends of the coin chutes. The forward end of each plate 39 is curved and recessed preferably as shown in Fig. 4 of the drawings. When the arms 90 34 are rocked the push plates 33 move forward in the coin ways and push the coin, which may be resting on the bottom 32 in said way in front of the push plate, under the controlling plate 39, causing said plate 95 to rise, carrying with it the end of the dog 24 and lifting the end of said dog free from the ratchet tooth or projection 23 on the wheel 22, thus leaving said wheel, the shaft 18, the star-wheel 19, and the turnstile, all free to turn. As the coin is moved forward it will pass into the recessed portion of the plate 39 as indicated by dotted lines in Fig. 3.

I provide means for holding the coin in 105 the coinciding portions of the coin way and coin chute, with the controlling plate 39 in the position to which it is raised by said coin, until the star-wheel and other parts moving therewith have been rotated. As 110 here shown this means consists of a series of laterally projecting arms 40 on the wheel 22. There are as many of these arms on each side of the wheel 22 as there are arms on the star-wheel 19. As shown in Fig. 1 of the 115 drawings a recess 41 is provided extending across the coin chute 38, and into this recess the ends of the arms 40 project. When the parts are in normal position the end of one of the arms 40 projects into the coin 120 chute and stands in position to hold the coin after it has been pushed forward with the controlling plate 39 in an elevated position. (See Fig. 3). The parts remain in this position until the person passing the turnstile in the direction indicated by the arrow *b* in Fig. 6 of the drawings, turns the star-wheel 19 and the wheel 22 one step. As 125 soon as the arm 40 passes from under the coin resting thereon said coin drops down 130

into and through the coin chute 8 into the box 5. As soon as the coin drops from the position shown in Fig. 3 down the chute the plate 39 and the dog 24 also drop, bringing 5 the end of the dog 24 into contact with the periphery of the disk 22, and causing it to engage the next shoulder or ratchet tooth 23, on said disk 22, and thereby preventing further movement of said disk, the shaft 18, 10 star-wheel 19, and the turnstile. Further movement of these parts is prevented until another coin is dropped into the machine and the lever 36 is pulled forward by the attendant so as to push the coin along in the 15 coin way under the controlling plate 39, to raise the dog 24 from engagement with the tooth on the disk 22.

In the operation of the machine it is intended that the attendant shall pull forward 20 the lever 36 thereby pushing the coin into position to unlock the disk 22 and the star-wheel, and thereby to release the turnstile. After the attendant brings forward the lever 36 it is intended that he shall release the 25 same and that said lever and the push plates 33 shall be automatically returned to their original position. I prefer to provide means by which this operation will be automatically performed as soon as the turnstile has 30 been moved sufficiently to operate the star-wheel.

Secured to the rock shaft 26 is a block 42 provided with arms 43 and 44 extending from the main part of the block in directions 35 substantially at right angles to each other. The end of the arm 43 has a screw-threaded hole through it, and a set-screw 45 is arranged in said hole. An arm 46 having a weighted end 47 is pivoted upon a standard 40 48 and is provided with a heel 49 that projects beneath the arm 43 and is adapted to be engaged by the end of the set-screw 45. Pivoted upon the arm 44 on the block 42 is a bell crank lever 50 having at the end of 45 one arm a hook 51 adapted to engage the top of a block 52. A spring 53 is provided on the pivot of the bell-crank 50 and said spring tends to hold the end of the hook 51 in contact with the top of the block 52, and 50 to cause said hook to engage said block whenever it is moved forward a sufficient distance to permit such engagement. The operation of this part of the device is as follows:

55 When the shaft 26 is rocked by the attendant's pulling forward the arm 36 the end of the screw 45 will press down on the rear end 49 of the arm 46, raising the weighted end of said arm and moving the 60 parts into the position shown in Fig. 3 of the drawings. The end of the hook 51 will slide over the top of the block 52 and will engage the top of said block as shown in Fig. 3 of the drawings. This will lock the 65 parts in the position shown in Fig. 3. When

the parts stand in this position the upright arm of the bell crank 50 will project into the path of one of the laterally extending arms 40 on the disk 22. As the disk 22 is rotated by the action of the turnstile, one of the 70 arms 40 on said disk will engage the upright arm of the bell crank 50 and will raise the hook 51 out of engagement with the upper end of the block 52. The weight 47 will now descend, and the action of this weight 75 through the rearwardly projecting end 49 of the arm 46, engaged by the end of the set-screw 45 will rock the shaft 26, thereby moving the parts back into normal position, as shown in Fig. 2 of the drawings, with the 80 push-plate in the coin way in position to permit the insertion of a coin in front of said plate. The parts will now all be in position for the insertion of another coin.

It may sometimes happen that the arm 36 85 will be moved forward so as to bring the parts into the position shown in Fig. 3, when a coin has not been deposited in the machine. For the purpose of releasing the parts if they get into this position I provide 90 a connection, preferably a wire 54, that has its lower end connected with the bell crank 50 and its upper end extending through a hole or recess in the top plate 10 of the casting. If the parts get into the position shown 95 in Fig. 3 when there is no coin in the machine, they can be restored to the position shown in Fig. 2 by pulling on the wire 54, thereby lifting the hooked end of the bell crank 50, permitting the weighted end of the 100 arm 46 to drop down into the position shown in Fig. 2, and moving the other parts operating therewith into the position shown in said Fig. 2.

It may sometimes happen that a person 105 passing the turnstile does not turn said stile the entire distance to which it should be turned to completely operate the star-wheel 19. I, therefore, preferably provide the shaft 18 with a ratchet wheel 55 having a 110 number of teeth corresponding to the number of arms on the star-wheel (see Fig. 5), and I provide an arm 56 on the rock shaft 26 which carries at its upper end a pawl 57 whose end rests upon the edge of the ratchet 115 wheel 55. If, in the operation of the turnstile, the star-wheel 19, shaft 18 and disk 22, have not been turned the exact distance required to bring the shoulder or ratchet tooth 23 against the end of the dog 24, and the arm 120 40 in proper position to support the coin next inserted, these parts will be moved by the engagement of the dog 57 with the teeth of the ratchet wheel 55, the next time the arm 36 is moved forward by the attendant. 125

I have shown in the drawings a machine constructed with two coin receiving devices, and adapted to be operated when a coin is inserted in either of the coin ways. As this machine is constructed it is intended to 130

have half dollars inserted in one way and 5 quarter dollars in the other way. As thus arranged the machine may be used to permit adults to pass the turnstile by paying an admission fee of fifty cents, which admission fee must be handed to the attendant, in the shape of a single coin. The attendant will receive the coin and deposit it in the half dollar opening. He will then pull the lever 10 36 and the person who has paid the fee can then turn the turnstile and pass into the inclosure.

If a child, or person who is entitled to admission for a twenty-five cent fee, desires 15 to enter, he will hand the attendant a twenty-five cent piece. The attendant will deposit this in the other opening and will pull the lever 36 as before, thereby, through the coin, releasing the star-wheel and permitting 20 the person who has paid the fee to pass the turnstile. The machine may, however, be constructed as a single machine with only one coin-receiving opening and one set of operating devices, and it can 25 then be operated only when a coin of the proper denomination has been presented to the attendant and he has dropped the same into the receiving opening, and has drawn forward the lever 36 thereby releasing 30 the parts and leaving the turnstile free to be turned a quarter revolution.

Instead of having two coin-receiving openings, I may provide three or more, said openings being arranged to receive coins 35 of suitable denominations, and, if preferred, one of the openings may be arranged to receive checks made of aluminum or other material and issued to persons who are entitled to enter the inclosure or pass 40 the turnstile without the payment of money.

This machine is designed to be used, among other places, at state and county fairs, expositions, etc. It sometimes occurs that different fees are charged for admission of adults and children. In such case the double machine is an advantage. It sometimes occurs also that employees and exhibitors are entitled to enter without the payment of money. In such case the machine 45 may be provided with a third receiving slot or opening in which a suitable check which is presented by the employee or exhibitor may be deposited by the attendant. The mechanism for receiving 50 such check and operating the machine upon the depositing of the same will be the same as that already described, the receiving way for the check being, of course, made of the proper size to receive the same, 55 and the controlling plate connected to the dog 24 being suitably proportioned and recessed to accommodate such check.

I may also prefer, in some instances, to make the machine adjustable, so that it may 60 be operated by a coin of any desired denomi-

nation. In Figs. 8 and 9 of the drawings I have shown the controlling plate 39 adjustably connected to the dog 24. As here shown, said plate is pivoted to the dog by a suitable pivot 58, and is provided with a locking screw 59, which may be made to engage either of the holes 60 or 61 in said dog. When the locking screw is in the hole 60, as shown in Fig. 8, a half dollar coin can be pushed under the controlling plate 39, 75 and a coin of this size will be required to operate the machine. When the locking screw is in the hole 61, as shown in Fig. 9, the machine can be operated by the insertion of a twenty-five cent piece. 80

I have shown the half dollar controlling plate 39 connected directly to the side of a plate 62 that is formed integrally with the dog 24 (see Fig. 7). The twenty-five cent controlling plate 39 may also be connected directly to said dog 24. I have, however, shown this controlling plate connected to an independent pivoted plate 63, which extends parallel with the dog 24. A short plate 64, shown by dotted lines in Fig. 7 90 and by full lines in Figs. 8 and 9, is secured to the plate 63, and extends beneath the dog 24. With this construction the plate 63 and the controlling plate 39 that is operated by the insertion of the twenty-five cent piece 95 are not moved when the machine is operated by the insertion of a fifty-cent piece, as the dog 24 moves away from the plate 64, which extends under said dog. When, however, a coin is inserted in the twenty-five cent coin 100 way the plates 63 and 64 will be moved, and will lift the dog 24 out of engagement with the tooth 23 on the disk 22.

I have shown in Figs. 11 and 12 a preferred construction for regulating the size 105 of the slot through the coin guard 12. As here shown a pin 65 is inserted through the end wall of the block and the end of this pin coincides with the line of the coin slot in said block. The pin may be moved in or 110 out and locked in any desired position by a set-screw 66. By pushing the pin inward the slot is partly covered and the insertion of coins above a desired diameter may be prevented. 115

I also prefer to provide a laterally adjustable block 67 arranged to slide upon ways 68 and having an adjusting screw 69. The edge of this block forms one of the side walls of the coin slot, and by adjusting the block 120 the width of the slot may be regulated and thereby the thickness of coins or checks that may be inserted, may be governed.

It is sometimes desirable to register the 125 number of coins that are put into the machine. Where a double machine is used a counting device may be arranged in connection with one or both of the controlling plates 39. In Fig. 13 of the drawings I have shown a suitable counter 70 preferably arranged on 130

top of the projection 13 on the cover and arranged to be operated by a pivoted dog or arm 71, connected to the controlling plate 39. Each time said controlling plate is raised 5 by the movement of a coin in the coin way, the registering or counting device will be operated. In this way a record of the number of coins inserted can be made.

It will be noted that by having the raised 10 projection 13 on the top plate 10 into which the controlling plates 39 rise as the coins are pushed forward in the coin ways, I am enabled to bring the coin ways and other parts of the mechanism close to the under side of 15 the main part of said top plate 10.

Where the machine is made double, or with two sets of operating devices, as shown, it will not usually be necessary to provide the adjustable feature, either for the controlling plate 39 or for the guards 12 over the coin-receiving slots, but, as before explained, the machine may be made as a single machine, having a single coin-receiving slot, coin-controlling plate 39, and other parts.

25 In this case it is desirable to have the adjustable features applied to the machine so that said machine may be arranged to be operated by a coin of one denomination and then be adjusted so as to require a coin of an other denomination.

30 It will be obvious that the details of construction may be modified in many particulars without departing from my invention.

I claim as my invention:

35 1. In a turnstile controlling mechanism, the combination, with means for locking said mechanism, of a coin way arranged to permit a coin to be moved edgewise therein, a coin push plate arranged in said way, a lever arranged to be operated independently 40 of the turnstile for actuating said push plate, and a controlling plate connected with said locking means, and arranged to be moved to release said locking means by a suitable coin inserted in said coin way and moved edgewise against said controlling plate by the movement of said push plate.

45 2. In a turnstile controlling mechanism, the combination, with a rotatable shaft, of a star-wheel mounted upon said shaft and arranged to be engaged by the turnstile, a disk upon said shaft provided with a series of ratchet teeth, a dog normally engaging one of said teeth and locking said disk against rotation, a controlling plate connected with said dog, a coin way and a push plate arranged to be moved manually, independently 55 of the turnstile to move a coin placed in said way against said controlling plate, whereby said locking dog will be released, permitting the rotation of said disk and turnstile.

60 3. In a turnstile controlling mechanism, the combination, with means for locking said mechanism, of a coin way, means ar-

ranged in said way for moving a coin edgewise therein in a plane parallel to the face of the coin, a controlling plate connected with said locking means and arranged to be moved manually, independently of the turnstile to release said locking means by engagement of the edge of a suitable coin inserted in the coin way and moved against said controlling plate, and means for returning the parts to normal position after each operation.

4. In a turnstile controlling mechanism, the combination, with means for locking said mechanism, of a coin way, means arranged in said way for moving a coin there- 70 in in a plane parallel to the face of the coin, a controlling plate connected with said locking means and arranged to be moved manually, independently of the turnstile to release said locking means by the engagement of 75 the edge of a suitable coin inserted in the coin way and moved edgewise against said controlling plate, and means for registering or counting the movement of said controlling plate.

5. In a turnstile controlling mechanism, the combination, with means for locking said mechanism, of a coin way, means arranged in said way for moving a coin edge- 80 wise therein, and an adjustable controlling 85 plate connected with said locking means, and arranged to be moved manually, independently of the turnstile to release said locking means by a suitable coin inserted in the coin way and moved edgewise against the 90 controlling plate.

6. In a turnstile controlling mechanism, the combination with means for locking said mechanism, of a coin way, an adjustable 95 guard controlling the passage of coins to 100 said way, means arranged in said way to be moved manually, independently of the turnstile for moving a coin edgewise therein, and a controlling plate connected with said locking means and arranged to be moved to 105 release said locking means by a suitable coin inserted in the coin way and moved edgewise against said controlling plate.

7. In a turnstile controlling mechanism, the combination, with means for locking said 115 mechanism, of a plurality of coin ways, means arranged in each of said ways to be moved manually, independently of the turnstile for moving a coin edgewise therein, a controlling plate in each coin way, and each 120 connected with said locking means and arranged to release the same by the movement of a suitable coin inserted in one of the coin ways and moved edgewise against the controlling plate in said way.

125 8. In a turnstile controlling mechanism, the combination, with means for locking said mechanism, of a coin-way adapted to have a coin moved edgewise therein, a push- 130 plate arranged in said way for moving said

coin, a lever for operating said push-plate; a controlling plate connected with said locking means and arranged to release said locking means by engagement therewith of the 5 edge of a suitable coin inserted in the coin-way and moved edgewise against said controlling plate, means for locking the lever, when moved to operate the push-plate without the insertion of a coin in the coin-way,

Copies of this patent may be obtained for five cents each, by addressing the "Commissioner of Patents, Washington, D. C."

and means for manually releasing said lever 10 and returning the parts to normal position.

In witness whereof, I have hereunto set my hand this 27th day of August, 1914.

JOSEPH WILLIAM BATES.
